(57) **CLAIM**

The ornamental design for a rock-like observation blind, as shown and described.

DESCRIPTION

FIG. 1 is an upper perspective view of a rock-like observation blind showing our new design.

FIG. 2 is a front elevational view thereof.

FIG. 3 is a right side elevational view thereof.

FIG. 4 is a rear elevational view thereof.

FIG. 5 is a left side elevational view thereof.

FIG. 6 is a top plan view thereof; and,

FIG. 7 is a bottom plan view thereof.

The broken line showing of a door and handle in FIGS. 1 and 2 is included for the purposes of showing environmental portions of the rock-like observation blind and forms no part of the claimed design.

1 Claim, 4 Drawing Sheets

FIG. 1

FIG. 3

FIG. 2

FIG. 5

FIG. 4

FIG. 7

FIG. 6
